Attorney

UNITED STATES PATENT OFFICE.

GEORGE W. WILMOT, OF HAZLETON, PENNSYLVANIA.

OIL-FILTER.

1,287,160.

Specification of Letters Patent. Patented Dec. 10, 1918.

Application filed August 15, 1916. Serial No. 114,985.

To all whom it may concern:

Be it known that I, GEORGE W. WILMOT, a citizen of the United States, residing in Hazleton, county of Luzerne, State of Pennsylvania, have invented certain new and useful Improvements in Oil-Filters, of which the following is a specification.

In the use of oils as lubricants, as, for instance, in automobiles where a considerable quantity of oil is carried in the crank case, they become dirty and filled with sediment and are now generally thrown away which entails considerable loss and waste.

My invention has for its main object to provide a filter suitable for filtering such oils which is simple in construction, efficient in operation and which may be employed economically for the purpose of filtering and cleansing the same so that they may be continued in use.

A further object is to provide suitable means whereby the oil to be filtered may be heated to a greater or less extent and thereby rendered more fluid whereby the impurities may be more readily and completely removed therefrom.

Other objects and advantages of my invention will be referred to in the detailed description thereof which follows or will be apparent from such description.

My invention is susceptible of being embodied in different forms of mechanical constructions but in the accompanying drawing I have shown the same embodied in a form of construction now preferred by me.

In the said drawing:

Figure 1 is a longitudinal sectional view of a filter embodying my invention; and

Fig. 2 is a transverse sectional view of the same taken on the line 2—2 of Fig. 1.

Referring to the drawing, 1 designates an outer casing having a transverse plate 2, constituting the bottom of an outer chamber 3. Situated below the bottom 2 is a second plate 4 forming a support for a lamp 5 employed for heating the water contained in the lower portion of the outer chamber 3.

The lamp 5 may be inserted into the space between plates 3 and 4 through an opening 6 formed in the lower part of the casing 1 and closed by means of a door 7.

Air enters the space between plates 3 and 4 through openings 8, three only of which are shown.

10 The outer casing 1 is supported upon projections 10, constituting feet.

15 designates an inner filtering receptacle or chamber for the reception of the oil to be filtered.

The upper end of the said chamber is provided with a laterally extending portion 16, the outer edges or ends of which rest upon lugs 17, projecting inwardly from the outer casing 1 adjacent to the top edges thereof. The top of the filter is closed by means of a 60 lid 18, the outer flanged edge of which fits within the upper end of the outer casing 1. 65 19 designates a bail or handle by means of which the filter may be moved readily from place to place.

70 21, 22 and 23 designate perforated plates situated inside and extending transversely of the inner chamber or receptacle 15, the said plates being supported upon inwardly projecting lugs 24 as shown. The plate 21, in 75 the construction shown, is situated at a point about midway between the bottom 25 of the inner chamber or receptacle 15 and the top of the same, although, if desired, its position within said chamber may be changed. The 80 plate 22 is situated a considerable distance nearer to the bottom of the said chamber or receptacle. The space between the plates 21 and 22 is filled with a suitable granular material 26, such as coke or charcoal. The plate 85 23 is situated still nearer to the bottom of the chamber. In the space between the plates 22 and 23 I have provided suitable filtering material such as fabric or cotton threads 27 packed more or less closely therein. The 90 space 29 below the perforated plate 23 is free and receives the oil which is filtered through the filtering substances 26 and 27.

95 The oil to be filtered is placed within the receptacle or chamber 15 and is indicated at 28. It flows by gravity toward the bottom of the said chamber and is collected in the space 29 from which it passes out through a pipe 30, the upper end of which terminates within the said space 29, as indicated at 31. 100 The said pipe extends from the said space through and is secured to the bottom 25 of the receptacle or chamber 15 and is provided with a number of coils as indicated at 32, which coils are situated within and covered by the water within the lower portion of the outer chamber 3 within the casing 1. The outer lower end of the said pipe terminates in a receptacle 33, constituting a trap, having a normally closed opening at 34 through 105 which sediment, carbon or other impurities which may have been trapped in the said

chamber 33 may be removed. 35 designates a pipe which extends upwardly from the trap or chamber 33 and which terminates a short distance below the lower end of an inverted truncated cone shaped deflector or distributor 36 for deflecting and causing the oil which is discharged from the short pipe 35 to scatter and contact with the water in the lower portion of the chamber 3, whereby it is more thoroughly cleansed and purified.

The deflector or distributor 36 is supported upon the lower end of the inner receptacle or chamber 15. It may be noted also that the pipe 30 passes through said deflector.

I have found that the deflector acts more satisfactorily if it be provided with a central reentrant portion 37 at its lower end into which the oil is discharged from the tube 35 and from which it passes around the angular edge 38 and thence upwardly along the lower surface of the said deflector or distributor.

25 The uppermost portion, indicated at 40, of the pipe within the space 29 is situated above the level 41 of the water in the outer chamber 3, so that there will be no danger that the water will flow in reverse direction from the chamber 3 through the said pipe 30 and discharge into the space 29.

The filtered oil which is discharged from the tube 35 passes upwardly through the water in the lower part of the chamber 3 and collects above the surface thereof in the annular portion of the said chamber intermediate the side walls of the chamber 15 and the sides of the casing 1.

40 The oil is withdrawn through a faucet 45 controlled by means of a valve 46.

By means of heat from the flame of the lamp 5, the water in the chamber 3 may be heated sufficiently to render the oil within the space 29 and within the pipe or tube 30 (including the coils 32) and the trap or chamber 33 quite fluid so that water and other impurities which may pass through the filtering material 26 and 27 may be readily separated therefrom and collected in the chamber 3 to be thereafter removed, as above described, through the faucet 45.

I claim:

1. In an oil filter, the combination of an outer receptacle, an inner receptacle, the

outer receptacle being adapted to contain 55 water in its lower end portion, filtering material within the inner receptacle for filtering oil which passes therethrough, means for withdrawing the filtered oil from the said inner receptacle and discharging it into the said water within the outer receptacle; said means comprising a tube having one or more coils situated in the said water, means for heating the said water and thereby rendering the oil 60 as it flows through the said tube more fluid 65 and a deflector against which the oil is discharged, said deflector having its sides inclined outwardly and upwardly for deflecting the oil discharge from the said tube laterally and upwardly in all directions in 70 the said water, substantially as described.

2. In a filter, the combination of an outer receptacle, an inner receptacle, the said outer receptacle being adapted to contain water in its lower end portion, filtering material 75 in the inner receptacle for filtering or cleansing oil which passes therethrough, means for withdrawing the filtered oil from the said inner receptacle and discharging the same into the said water, a truncated cone shaped 80 deflector situated within the water, said deflector being provided with a reentrant portion at its lower end, the oil being discharged from the said withdrawing and discharging means into the depression formed 85 by the said reentrant portion from which depression the oil passes laterally and upwardly through the said water to the top thereof, substantially as described.

3. In a filter, the combination of an outer 90 receptacle, an inner receptacle, the said outer receptacle adapted to contain water in the lower end portion thereof, filtering material within the said inner receptacle for filtering oil placed in the said inner receptacle, means 95 for withdrawing the oil from the said inner receptacle, said means comprising a tube one end of which terminates in the said receptacle and a trap situated within the said water within which the other end of the said tube terminates, the said trap having a discharge opening through which the oil which is delivered to the said trap from the said tube is discharged into the said water. 100

In testimony that I claim the foregoing as 105 my invention I have hereunto signed my name, this 8th day of August, A. D., 1916.

GEORGE W. WILMOT.
